UNITED STATES PATENT OFFICE.

CONRAD TRIER, OF CHICAGO, ILLINOIS.

CAR-DOOR.

SPECIFICATION forming part of Letters Patent No. 409,077, dated August 13, 1889.

Application filed April 4, 1889. Serial No. 305,995. (No model.)

To all whom it may concern:

Be it known that I, CONRAD TRIER, a citizen of the United States, residing at Chicago, in the county of Cook and State of Illinois, have invented a new and useful Improvement in Car-Doors, of which the following is a specification.

My invention relates to the class of doors usually provided upon freight-cars employed particularly or incidentally in the transportation of grain, which are known as "grain-doors," and are designed when in use to close only the lower portion of the door-opening in each side of the car, and when not in use to be raised to the top of the door-opening and swung back to a substantially horizontal plane, whereby the said opening is left clear and the door itself placed in the condition of being out of the way.

Grain-doors of the above class hitherto commonly employed have been arranged to slide upon stationary guide-rods secured to the door-posts inside the car and on opposite sides of the door-openings. As cars used in the transportation of grain are also used largely in the transportation of other freight, as lumber, for instance, the guide-rods referred to are frequently in the way, and are liable to become bent, displaced, or broken in the loading and unloading or the jarring against them while in transit of freight other than grain, thereby impairing or destroying their utility as guides.

My object is to provide a grain-door of the above class and of improved construction, in the employment of which stationary guide-rods may be dispensed with, whereby when the door is turned to its horizontal or substantially horizontal position no part of the grain-door mechanism shall remain below the top of the doorway which can materially interfere with the use of the car for freight of any description or be itself injuriously affected by such use.

My invention consists in the general construction of my improved grain-door, and also in details of construction and combinations of parts, hereinafter described and claimed.

In the drawings, Figures 1 and 2 are views in sectional elevation of the interior of a

freight-car provided with my improved grain-door in different conditions. Fig. 3 is a section taken on the line 3 3 of Fig. 1 and viewed in the direction of the arrows; Figs. 4 and 5, 53 similar views of the last, showing the grain-door in different positions; Fig. 6, a detail in perspective, and Figs. 7 and 8 broken views of modifications.

A is a freight-car, of which A' is the floor 60 and A² the roof.

B B are the door-posts, and B' a projection, which may be afforded by any suitable means, as by causing the "door-cap" to extend into the car above the door-opening.

C is a grain-door proper of common construction and provided with the hinged extension C'.

D D are loose hangers, preferably in the form of metal rods, pivotally secured at one 70 end to brackets t and provided at their opposite ends with eyes s, which receive and afford bearings for pins s', projecting from the lateral edges of the grain-door toward the upper end q thereof. The brackets t are secured to 75 the "plate" B² of the car, and the rods D are of a length to permit the door, as it hangs by means of its pins s' at the eyes s in the rods, barely to touch the floor of the car with its lower edge q'. The hangers thus operate to 80 maintain the door in a vertical position against the door-posts.

E E are angle plates or keepers secured to the floor of the car on opposite sides of the door-opening, and are arranged to afford confinement with the door-posts for the lower plated corners x of the door to enter and fit snugly into. The keepers E are beveled on both inner faces r, as shown in Fig. 6, to facilitate the entrance of the corners x of the door and 90 guide the said corners as the door descends against the door-posts, maintaining the corners, when adjusted, firmly in contact with the latter and at the same time preventing lateral shifting of the door.

To open the door, it is first raised until its lower end clears the keepers E, when it is folded by turning it at the said end upward to the position shown in Fig. 4, and again folded with the hangers by swinging it at 100 the end q up to a horizontal position, in which it is supported by a catch o or other suitable

fastening means suspended from the ceiling of the car. When the door is turned upward to a horizontal plane, the end q' is sustained by the projection B' .

- 5 Hooks $p p$ should be provided on the door-posts, as shown, to engage the upper end of the door and prevent raising of the latter by a jarring motion of the car. When the door is provided with the hinged extension C' , it is
 10 necessary to lower the latter and secure it when it is desired to raise the door. The securing may be effected by means of a pivotal fastener n upon the door, as shown.

Although I prefer that the hangers D shall
 15 comprise rods, as described, a flexible hanger—such as rope, chain, or the like—may be substituted to operate in substantially the same manner, and I desire to include under the general term of "hangers" all such
 20 obvious equivalents for the rods shown.

Instead of the projection B' , lateral projections, preferably in the form of hooks y , as shown in Fig. 7, may be provided upon the grain-door proper to engage the hangers D ,
 25 and rest upon them as the door is suspended in its horizontal position to sustain the end q' ; or lugs z may be provided upon the hangers, as shown in Fig. 8, to extend under the door when the latter is folded and operate in
 30 the same manner to sustain the end q' of the door.

What I claim as new, and desire to secure by Letters Patent, is—

1. In a freight-car, the combination, with
 35 the grain-door C , of hangers D , pivotally secured toward opposite ends, respectively, to

the inside of the car near the top and at opposite sides of the door-opening and to opposite lateral edges of the door C , toward the upper end of the latter, a support for the end q' of the door, and a support for the end q of the door suspended from the ceiling of the car, substantially as described.

2. In a freight-car, the combination, with the grain-door C , of hangers D , pivotally secured toward opposite ends, respectively, to the inside of the car near the top and at opposite sides of the door-opening, and to the opposite sides of the door C , toward the upper end of the latter, angular keepers E , secured to the floor of the car at opposite sides of the door-opening, and each provided with two beveled faces $r r$, a support for the end q' of the door, and a support for the end q of the door suspended from the ceiling of the car, substantially as described.

3. In a freight-car, the combination, with the grain-door C , of rods D , pivotally secured toward one end inside the car, near the top and at opposite sides of the door-opening, and provided toward their opposite ends with eyes s to receive pins s' , which project from the lateral edges of the door toward the top thereof, a support for the end q' of the door, and a support for the end q of the door suspended from the ceiling of the car, substantially as described.

CONRAD TRIER.
